(54) **WATER WHEEL, OBLIQUE**

(76) Inventor: **Ralph Bulkley**

Ralph Bulkley
Letters Patent date 7th August 1831

The schedule referred to in these letters patent,
and making part of the same containing a description
in the words of the said Ralph Bulkley his
self of his improvement, being an "oblique water
wheel."

To all persons to whom these presents shall
come, & Ralph Bulkley of the city of New York
in the county and State of New York, making greeting:
Be it known that the said Ralph Bulkley, have
invented & constructed, made, and applied to use a new
and useful improvement, being an oblique water wheel
a machine to be used for the purpose of pumping
water, batteries or a part of one of any description, or
other liquids or boats of any description, whether the
same are moved by steam or other power, either up
in the ocean, lakes, bays, harbors, rivers, creeks
or canals; also to be used in a stationary position
in currents produced by tide in harbors, or other
places or in rivers, creeks, canals or streams of any
description either where there is a rise or fall or
not, for the purpose of moving mills of all descrip-
tions or manufactures of all descriptions for the
purpose of forcing or pumping water from rivers,
harbors, creeks, canals or other places for the purpose
of lifting vessels; or for any other uses that may be
required. The said improvement is called the "oblique
water wheel;" and may be specified in the words
following, to wit, four or more paddles arranged
upon the opposite sides of an axle or shaft, in a

diagonal or oblique position to the direction of the shaft, and all inclining in the same direction, making an angle with the shaft or axle of forty-five degrees, or a quarter or less angle as may be found convenient, the paddles being placed upon the shaft in a position similar to the position of the sails of a windmill; but varying in obliquity as convenience may require. And the wheel may consist of a shaft or axle and one or more sets of paddles placed upon it, at a short distance from each other, models of which are deposited in the Patent Office; and one of the forms or shapes of said wheel may be represented in the following manner.

Let the circumference of a circle be divided into four equal parts by lines drawn through the centre; and let each quarter of the circle be bent from its position in an equal degree, keeping the centre point together, and making an angle at the circumference of each quarter with the former circumference of forty-five degrees, or such other angle as may be found convenient, and in such a manner that the circumference of the former circle shall run through the centre or middle part of the circumference of each quarter of the circle so bent from its former position.

If the wheel is to be applied for the purpose of propelling steam ships, or other vessels or boats, a single set of paddles is considered preferable; but if applied stationarily in steamers or currents of water for any of the purposes above mentioned, the wheel may consist of one, or all, or several sets of paddles, secured at proper distances from each other upon the shaft or axle. And in either case the wheel may be wholly or partially immersed in the water as may be preferred or

found convenient, and the surface of the water is in a direction ^{parallel} ~~opposite~~ to the direction of the shaft or axle, whether as in its form, as above described, it differs from all other wheels in use, for any of the purposes aforesaid.

The wheel above mentioned may be applied to the stern, bottom, or sides of a steam battery, steam ship, or other vessel or boat, and may be either wholly or partially immersed in the water. If applied to the stern of a ship, vessel, or boat, a shaft or axle enters through the stern at a suitable distance below the surface of the water to connect the wheel to be either partially or entirely immersed as may be required, and upon this shaft or axle the paddles are secured in the manner above mentioned. If used at the sides or bottom of the ship, vessel, or boat, the wheel will also be connected with the machinery by means of a shaft or axle entering the vessel or boat, and the motion of the shaft or axle being thereby the elliptic action or pressure of the paddles upon the water produces a strong propelling power.

If placed in a current produced by the tide when the current moves part of the time in one direction, and part of the time in the contrary direction, the wheel will move with equal rapidity and equal force, whether the water strikes against the front or rear; and the wheel may be wholly or partially immersed in the water as the situation in which it is used may require. The angle or elliptic direction of the paddles may also be varied, according to the rapidity of the current, or as will best answer the purpose designed by using it, such as forcing a current of water or moving mills or manufactures, as above mentioned; or for any other purpose where a force is produced, thus obtained, may be applied to advantage, and where used for these or other purposes, the axle or shaft of the wheel

will be connected with the machinery to be moved by it.

The shaft of the axle of the wheel, above described, may be made of wood or iron, or other metallic substance, as may be found most suitable in the situation in which the wheel is used, and the paddles or buckets may be made of wood, copper, iron, or other substance, and of great or less thickness and strength according to the situation in which used, and the power intended to be gained by it, and to be secured firmly to the shaft or axle by means of nuts or bolts, in various ways as may be most convenient. And the paddles may be made in the form of a quarter of a circle, or of a square, oblong, triangular, or other shape. And the paddles may be separate, and placed separately upon the shaft or axle, and secured to the shaft, as a key is secured to its handle, with the addition of nuts or bolts through the shaft; or the paddles may be joined or connected at the center, and secured together upon the shaft or axle, by means of a hole through the center of the wheel through which the shaft or axle may be inserted in such other manner as may be found convenient.

Among the advantages of the wheel or machine above described, the following may be enumerated: to wit, that it may receive either wholly or partially under water, as may be found convenient; and it is believed that the same force acting upon a wheel, constructed as above described, upon the principle of oblique pressure, would repel a ship's rudder or boat faster than if acting upon the wheels in common use are exposed; and such a wheel being attached to a ship's battery, or ship of war, and being wholly immersed in the water, would not be exposed to the same accidents from shot to which the wheels in common use are exposed; and being wholly

increased its motion would not be materially ~~impaired~~^{improved} by passing a dashing sea; and when used stationary in factories, stores, docks, canals, or other structures an adequate force may be obtained by means of the oblique pressure of the stream upon the wheel; and may be applied to the purposes above mentioned or to other purposes when a force or power thus obtained may be found convenient or useful.
